AMUSEMENT DEVICE

Pendleton G. Watmough, Devon, Pa.

Application June 10, 1933, Serial No. 675,208

12 Claims. (Cl. 273—1)

My invention comprises a novel type of sporting game or amusement device having general and special features as hereinafter set forth, whereby interest and entertainment is afforded 5 to the users thereof.

My invention comprises a main supporting member of convenient length with brackets attached thereto with one or more wires or carriers extending between said brackets in combination with a plurality of elements freely sliding 10 on said carriers and zone limiting devices secured in definite relation therewith, adapted to restrict the movement of said sliding elements.

The nature, objects and other novel features 15 of my invention will be more fully understood by reference to the following specification taken in conjunction with the accompanying drawing forming a part thereof and with the claims hereinafter appended. In the aforesaid drawing, 20 which shows a preferred form of construction like parts are designated by similar letters.

Fig. 1 is a plan view showing the general assembly of a device constructed according to my invention.

Fig. 2 is a section taken through a supporting sleeve, adapted to slide over a transverse joint in the main longitudinal supporting member, whereby its length on disassembly may be halved to facilitate shipment.

Fig. 3 is a partly sectionalized view of one of the disc shaped sliding elements.

Fig. 4 shows detail of mechanism whereby tension of wires or carriers may be readily adjusted.

Fig. 5 is an enlarged view of one of the zone limiting elements, comprising a tightly wound spiral spring passing through and supported in an aperture provided therefor in the main supporting member.

Screw ends are provided for the spring whose weight adds an adjustable inertia to any sudden movement of the spring as when suddenly struck by one of the sliding elements; said screw ends also add an attractive finish to the appearance.

I will now describe the details of the drawing.

In Fig. 1, 1 represents the main supporting member with a transverse joint through the center securely held by the sliding sleeve 2, a section through which is shown in Fig. 2. 3, 3 are the end brackets, secured in apertures in the supporting member, from which depend the carrier or guide wires 4, 4, which pass through holes shown in the ends of the brackets. 5, 5 represent several of the sliding disc-like elements 55 which are loosely suspended on the carrier wires

by means of center holes through which the wire freely passes. A partially sectionalized view of aforesaid sliding element is shown in Fig. 3, wherein 4 is the carrier along which the disc 5 may freely slide. The limiting devices 6—6 are likewise supported in apertures provided in the main frame 1, an enlarged view being shown in Fig. 5 wherein 7 is an adjusting screw which may be inserted in the spring to the desired degree, and 8 a pin driven through supporting member 1 securely maintaining the spring 6 in its proper position. In Fig. 1, 9 is a bifurcated winding key shown in enlarged and fuller detail in Fig. 4. It is inserted in the hole 10 passing through member 1, which hole intersects the 15 larger aperture 11 made at right angles thereto, and through which the carrier wire 4 is passed between the prongs of key 9. 12 is a locking key which not only serves as a lever in twisting key 9 and so winding to tension the carrier 20 wire 4, but also may be used to lock key 9 in position against the untwisting tension of the carrier, by placing 12 in the position as shown where its prongs clench the headed nail 13. In Fig. 1 two striking wands 14, 14 are provided by 25 which the disc-shaped elements may be quickly struck and slid to their desired goal. The zone over which said wands can be used is limited to pre-determined bounds by the tie strings 15, the latter being attached to some convenient 30 point of the frame work. In the operation of my device two players participate, each holding with one hand an end handle of the supporting frame with a striking wand in the other hand; the object being to place the button shaped ele- 35 ments in predetermined zones, subject to certain restrictions and despite the competitive actions of the players.

From the foregoing it will be seen that I provide a thoroughly practical, simple and novel 40 type of apparatus of the character described. Therefore without specific limitation to the apparatus herein shown and without enumerating equivalents, I claim as new and desire to secure by Letters Patent the following:

1. Apparatus of the character set forth comprising a plurality of transverse guides, a plurality of elements slidably supported on each of said guides, means defining a zone at an end of each of said guides in which the slidable ele- 50 ments of the guide may lodge, and means defining a plurality of restricted playing areas each embracing the zoned end of one of the guides and the other end of another of the guides.

2. Apparatus of the character set forth com- 55

- prising a pair of substantially parallel transverse guides, a plurality of elements slidably supported on each of said guides, means defining a zone at an end of one of the guides and at the opposite 5 end of the other guide in which the slidable elements of the respective guides may lodge, and means defining restricted playing areas respectively embracing the adjacent ends of both guides.
10. 3. Apparatus of the character set forth comprising a plurality of transverse guides, a plurality of elements slidably supported on each of said guides, means defining a zone at an end of each of said guides in which the slidable elements of the guide may lodge, and means defining a plurality of restricted playing areas each embracing the zoned end of one of the guides and the other end of another of the guides, and means for propelling the said elements longitudinally on the guides.
15. 4. Apparatus of the character set forth comprising a pair of substantially parallel transverse guides, a plurality of elements slidably supported on each of said guides, means defining a zone at an end of one of the guides and at the opposite 20 end of the other guide in which the slidable elements of the respective guides may lodge, and means defining restricted playing areas respectively embracing the adjacent ends of both guides, and means for propelling the said elements longitudinally on the guides.
25. 5. Apparatus of the character described comprising a plurality of transverse guides, supporting members therefor, a plurality of elements 30 slidably mounted on each of said guides, and flexible goal devices secured to said supporting members in juxtaposition to said guides to apportion them into zoned regions and forming a haven at one end into which the slidable elements may 35 be propelled.
40. 6. Apparatus of the character set forth comprising a plurality of substantially parallel and horizontal guide lines and a plurality of slidable elements freely mounted thereon, in combination with flexibly constructed goal posts secured in juxtaposition to said guide lines so as to apportion them into defined zone sections, and means for propelling said slidable elements into such 45 sections.
45. 7. Apparatus of the character described comprising a plurality of transverse guides, a plurality of elements slidably supported on each of said guides, resilient goal devices defining a zone at an end of each of said guides in which the 50 slidable elements of the guide may lodge, and means for limiting the field of action of the
- contesting players to playing areas adjacent to the opposing ends of the aforesaid guides.
8. Apparatus of the character described comprising a plurality of substantially parallel and horizontal guide lines and a plurality of slidable elements freely mounted thereon, in combination with flexibly constructed goal devices secured in juxtaposition to said guide lines adapted to retard free access of the aforesaid slidable elements to defined zone sections thereof, means for propelling said slidable elements past said goal devices into such sections, and means for restraining the field of action of the contesting 55 players to their respective zoned locations.
9. In an apparatus of the character described the combination of a plurality of substantially parallel and horizontal tensioned guide lines, supporting member therefor, slidable elements mounted on said guide lines, flexibly constructed goal devices arranged to define on said guide lines zoned regions wherein the aforesaid slid- 10 able elements may lodge, and means for adjusting the tension of said guide lines.
10. An amusement device of the character described, comprising a frame work carrying trans- 25 verse guide lines supporting a plurality of slidable elements, flexible goal devices secured to said framework near opposing ends of the aforesaid guide lines and adapted to interfere with the free passage of said slidable elements past said 30 devices, and means for propelling said slidable elements along the said guide lines.
11. An amusement device of the character described comprising substantially parallel trans- 35 verse guide lines each carrying a plurality of slidable elements, flexible goal devices secured near opposing ends of said guide lines adapted to interfere with the free passage of aforesaid slidable elements, means for propelling said slid- 40 able elements along the aforesaid guides, and a flexible barrier device to limit the field of action 45 of the contesting players to areas adjacent to the opposing ends of the respective guide lines.
12. An amusement device of the character described comprising a supporting member carry- 50 ing substantially parallel transverse guide lines with slidable elements mounted thereon, spring formed goal devices secured on said support member and adapted to present a hazard to the free passage of said slidable elements, a barrier device for limiting the field of action of the contesting players to areas adjacent to opposing ends of said guide lines, and an adjustable joint mechanism in aforesaid support member adapted to permit reduction of its lineal dimension.

PENDLETON G. WATMOUGH. 55
